CLAIM

The ornamental design for the ceiling track for lamp as shown and described.

DESCRIPTION

FIG. 1 is a front, right, and top perspective view of the ceiling track for lamp, showing my new design;

FIG. 2 is a rear, left, and bottom perspective view thereof;

FIG. 3 is a front view thereof;

FIG. 4 is a rear view thereof;

FIG. 5 is an enlarged left side elevation view thereof;

FIG. 6 is an enlarged right side elevation view thereof;

FIG. 7 is a top plan view thereof;

FIG. 8 is a bottom plan view thereof;

FIG. 9 is an enlarged view of an encircled area labeled “9” in FIG. 1; and,

FIG. 10 is an enlarged view of an encircled area labeled “10” in FIG. 2.

The broken lines depict portions of the ceiling track for lamp that form no part of the claimed design. The article is shown with a symbolic break. The appearance of any portion of the article between the pair of break lines forms no part of the claimed design. The dot-dash broken lines shown in FIGS. 1, 2, 9, and 10 surrounding portions of the ceiling track for lamp depict the boundaries of enlargement and form no part of the claimed design.
